UNITED STATES PATENT OFFICE.

OTTO C. F. MEISEL, OF BOSTON, MASSACHUSETTS, ASSIGNOR TO MEISEL PRESS MANUFACTURING COMPANY, OF BOSTON, MASSACHUSETTS, A CORPORATION OF MASSACHUSETTS.

SHEET-HANDLING MECHANISM.

Application filed May 6, 1924. Serial No. 711,364.

This invention relates to sheet handling mechanism and finds a particular application in the case of a cylinder or like sheet carrier having grippers which are operated at different times or in different positions. The object is to provide an efficient and compact mechanism for handling the sheet. Examples of such mechanisms as I have referred to are the intake and delivery mechanisms in a multi-couple, multi-color press of the ring gear type, such, for example, as that illustrated in the patent to Charles A. Meisel 1,399,360, dated Dec. 6, 1921, and as an example of my invention I have here 15 shown the transfer and delivery mechanism of a two color press of that type.

The example of my invention just referred to will be readily understood by reference to the following description taken in 20 connection with the accompanying drawings, wherein:

Fig. 1 is a fragmentary sectional view longitudinally of the press showing the transfer and delivery mechanisms; 25 Fig. 2, on a larger scale, is a section on the line 2—2 of Fig. 3 showing principally the mechanisms governing the operation of the transfer cylinder; and

Figs. 3 and 4 are sections on the lines

30 3—3 and 4—4 of Fig. 2, respectively (the ring gear and its grippers are omitted).

Referring to Fig. 1, I have there shown certain portions of a press of the ring gear type such as is disclosed in the patent above referred to to which reference may be made for a fuller description. The sheet which is to be printed is carried by grippers 5 extending between a pair of ring gears 7 and after the printing operation is transferred from 40 these grippers to the grippers 9 of a transfer cylinder 11 tangent interiorly to the sheet path and after being carried around the cylinder 11 is delivered to grippers 13 of a suitable delivery device such as the chain 15 which moves through a path exteriorly tangent to the sheet path at substantially the same point of tangency as the cylinder 11. The general method by which the sheet is carried by grippers 5 into the open grippers 45 9 which close upon the same substantially at the common point of tangency as the grippers 5 open to release it and the manner in which the sheet after being carried around the cylinder 11 by the grippers 9 is carried

into the open grippers 13 which close on the 55 same while the grippers 9 open to release it will be obvious to those skilled in the art and is essentially similar to the operation of feeding in the paper described in detail in the Meisel patent above referred to. For 60 present purposes it is sufficient to note that the opening and closing of the grippers 9 in taking the sheet from the main grippers 5 of the ring gears is timed somewhat differently or takes place at a somewhat different point in the revolution of the transfer cylinder 11 from their opening and closing as they deliver the sheet to the grippers 13 of the delivery chains. The mechanism herein illustrated as an example of my invention has for its purpose the proper control of the grippers 9 on alternate revolutions of the transfer cylinder 11.

Referring now to Figs. 2 and 4, the gripper mechanism 9 comprises a gripper shaft 17 carrying a pinion 19 which is actuated in well known manner by a sector 21 on a rock shaft 23 carried by an arm 25 fixed to and rotating with the trunnion shaft of the transfer cylinder 11, which shaft 23 may be 75 rocked by means of the arm 27 carrying a cam roll 29 which is adapted to be operated alternatively (see Fig. 2) by cams 31 and 33. The cams 31 and 33 are mounted on 80 swinging arms 35 and 37 respectively so that 85 they may be moved inwardly at proper times to cooperate with the cam roll 29 or swung outwardly to clear the same and herein they are moved in to cooperate with the cam roll 29 alternately on successive rotations of 90 the cylinder 11.

To control the swinging of the arms 35 and 37 I make use of a cam in the form of an annular disc 39 organized concentrically with the axis of the cylinder 11 and suspended (see Fig. 3) just inside the frame 41 of the press on rolls 43, the inner face of this annulus having a cam groove or an eccentric groove 45 adapted to actuate the arms 35 and 37 through suitable mechanism 95 presently to be described. In the present embodiment of the invention the cam 39 is a half speed cam and has a planetary drive, being formed as an internal gear and being driven by the intermediate pinions 47 mounted on shafts 49 in the frame from a gear 51 fixed to the trunnion of transfer cylinder 11. Thus, the cam and its mecha-

nism are compactly arranged adjacent the frame and organized concentrically with the cylinder, the grippers of which it controls.

In the present embodiment of the invention the lever 35 has a cam follower roll 53 entering the eccentric groove 45 and it will be clear from Fig. 2 that since the internal gear 39 in which this groove is formed operates at half the speed of the gear 51 and consequently of the transfer cylinder 11, the arm 35 is swung inwardly on alternate revolutions of that cylinder to operate the cam roll 29 to actuate the gripper shaft 17.

The arm 37 carrying the other cam 33 may be operated in any suitable manner in alternation with the arm 35. In the embodiment of the invention shown it is independently actuated from the cam groove 45. Herein movement of the arm 37 is controlled by a portion of the cam groove substantially diametrical to the portion actuating the arm 35 and thus since the cam or gear 39 rotates at half the speed of the transfer cylinder, the high point will act to move the two levers respectively substantially in the same phase of alternate revolutions of the transfer cylinder. Operatively to connect the arm 37 with the cam groove that arm may be in the form of a lever of the first class and may be joined by the connecting rod 55 to an arm of a bell crank lever 57, the other arm of which carries the cam roll 59 entering the groove 45 at a point substantially diametrical to the cam roll 53. While in the embodiment of the invention shown the two rolls or followers are diametrical, as seen in Fig. 2, it will be understood that the cams 31 and 33 act on the follower 29 which operates the gripper shaft in different angular positions of the latter as they are presented in different angular positions relative to the center of the transfer cylinder as is necessitated by the requirements of the mechanism for opening and closing the grippers 9 at somewhat different times on alternate revolutions of the cylinder.

I have described in detail the particular embodiment of my invention herein shown. It will be obvious, however, that it is capable of many other applications and of embodiments in different forms. The specific character of the description which has just been given is not therefore to be understood as in any way definitive of the scope of the invention as the purpose has been simply to make the construction and operation of the form shown amply clear.

What I claim as new and desire to secure by Letters Patent I shall express in the following claims.

1. In sheet handling mechanism, in combination, a cylinder and its grippers, means for actuating the grippers at desired times comprising a movable cam and means for

shifting the same comprising a follower connected therewith and a cam cooperating with said follower organized about the axis of the cylinder and comprising an internal gear driven from the cylinder.

2. In sheet handling mechanism, in combination, a cylinder and its grippers, means for actuating the grippers at desired times comprising a movable cam and means for shifting the same comprising a follower connected therewith and a cam cooperating with said follower organized about the axis of the cylinder concentrically thereto.

3. In sheet handling mechanism, in combination, a cylinder and its grippers, means for actuating the grippers at different times on successive revolutions of the cylinder comprising a pair of levers having gripper actuating cams, a rotary member having an eccentric groove, the levers having followers received in said groove at different points and means for rotating said member in timed relation to the cylinder.

4. In sheet handling mechanism, in combination, a cylinder and its grippers, means for actuating the grippers at different times on successive revolutions of the cylinder comprising a pair of levers having gripper actuating cams, a rotary member having an eccentric groove, the levers having followers received in said groove at different points and reduction gearing between said cylinder and member.

5. In sheet handling mechanism, in combination, a cylinder and its grippers, means for actuating the grippers comprising a gear on the cylinder, intermediate gears meshing therewith, a driven internal gear suspended coaxially of the cylinder, a cam groove in said gear and a movably mounted gripper actuating cam having a follower cooperating with said groove.

6. In sheet handling mechanism, in combination, a cylinder and its grippers, means for actuating the grippers at different times on successive revolutions of the cylinder, comprising a member organized coaxially of the cylinder, means for driving it therefrom at reduced speed, a cam groove in said member, a pair of cams or trips adapted alternately to operate the grippers and levers for moving said cams having followers received in said groove in different angular positions.

7. In sheet handling mechanism, in combination, a cylinder and its grippers, a half speed cam organized coaxially of the cylinder and having a cam groove and gripper operating devices adapted to be moved into and out from operative position on successive revolutions of the cylinder and including a cam follower cooperating with said groove.

8. In sheet handling mechanism, in combination, a cylinder and its grippers, a half

- speed cam comprising an internal gear surrounding the cylinder shaft and intermediate gears driving said gear from the shaft, said cam having an eccentric groove and gripper-operating devices adapted to be moved into and out from operative position on successive revolutions of the cylinder and including a cam follower cooperating with said groove.
9. In sheet handling mechanism, in combination a cylinder and its grippers, means for actuating the grippers at different times on successive revolutions of the cylinder comprising a pair of levers having gripper

actuating cams, a rotary member organized coaxially of the cylinder and driven at a slower speed and having an eccentric groove, one of said levers having a follower received in the groove, and means for swinging the other lever in alternation with the first.

10. The structure as described in claim 9 wherein the rotary member forms an internal gear and is pinion driven from the cylinder shaft.

In testimony whereof, I have signed my name to this specification.

OTTO C. F. MEISEL.
